UNITED STATES PATENT OFFICE.

THEODORE AMNELIUS, OF SOUTH FRAMINGHAM, MASSACHUSETTS.

PROPELLER.

933,151.

Specification of Letters Patent. Patented Sept. 7, 1909.

Application filed April 6, 1909. Serial No. 488,245.

To all whom it may concern:

Be it known that I, THEODORE AMNELIUS, a citizen of the United States, residing at South Framingham, in the county of Middlesex and State of Massachusetts, have invented certain new and useful Improvements in Propellers; and I do hereby declare the following to be a full, clear, and exact description of the invention, such as will enable others skilled in the art to which it appertains to make and use the same.

This invention relates to propellers, adapted for use with any approved craft moving in a fluid medium.

15 An object of the invention is to provide a propeller having a plurality of blades positioned for engagement with the fluid medium and of conformation to prevent the centrifugal discharge of the medium from the ends of the propeller blades.

20 A further object of the invention is to provide a propeller having integral blades attached to a hub of improved construction.

25 With these and other objects in view, the invention comprises certain novel constructions, combinations and arrangements of parts, as will be hereinafter fully described and claimed.

30 In the drawings:—Figure 1 is a view of the improved propeller in rear elevation. Fig. 2 is a view of the propeller in side or edge elevation. Fig. 3 is a view of the hub with the propeller blade broken away. Fig. 4 is a view similar to Fig. 2 with the hub sections separated.

35 Like characters of reference designate corresponding parts throughout the several views.

40 Like co-pending application No. 472,326, the device which forms the subject-matter of this application comprises a plurality of propeller blades mounted side by side and as in that application is here illustrated as composed of three sub-blades. In the present instance the sub-blades are provided with 45 a plurality of curves as 10, 11, 12 and 13, the curve 10 being preferably provided with two faces, 11 with three faces, 12 with four faces, and 13 with five faces, such faces being 50 preferably plain and set at an angle to its adjacent face as clearly shown at Fig. 2. In addition to the number of faces increasing from 10 to 13 the size of the curves also increases, the size of the faces remaining 55 substantially the same and the area of the curved portions increasing as the number of

faces. The sub-blades are, of course, as here shown formed integral or rigid with the hub and as shown at Fig. 1 three of the sub-blades are connected with each of the 60 hub sections. The device is mounted on a shaft as 14 and the hub sections are shown as a whole at 15, 16 and 17. The hub section 15 is intended to be the first hub section upon the shaft 14 and is provided with 65 a recess 18 positioned to receive the overhang 19 of the hub section 16, said hub section 16 being also provided with a recess 20 proportioned to receive the overhang 21 of the hub section 15.

70 Preferably the hub sections are provided for convenience with as many of such recesses and overhangs as the number of blades so that one of the overhangs is practically formed by the inner extremity of the blade 75 while the recess is disposed between adjacent blades. The hub section 16 is also provided with a recess 22 adapted to receive the overhang 23 of the hub section 17 which, in like manner, is provided with a recess 24 adapted 80 to receive the overhang 25 of the hub section 16. The recesses and overhangs of the hub sections 16 and 17 are the same essentially as the recesses and overhangs of the sections 15 and 16 and similarly disposed.

85 As shown in Fig. 4 the hub sections are separated showing the recesses and overhangs while in Fig. 3 the hub sections are shown in engaging position and held in such position by the nut 26 upon the extremity of 90 the shaft.

95 While the propeller has been here shown as provided with three sub-blades it is to be understood that any approved number of blades may be employed and in case more than three blades are employed all the intermediate blades are provided with hub sections similar to the hub sections 16, the outer hub sections only corresponding to the hub sections 15 and 16.

100 What I claim is:—

1. A propeller provided with a blade having a plurality of curves made up each of a plurality of plain faces disposed at an angle to each other with the number of faces increasing from the center to the peripheral end of the blade.

10 2. In a propeller, a blade having a plurality of curves increasing in area from the center to the peripheral end, such curves being composed of plain surfaces of substantially equal width disposed at angles to each other.

3. In a propeller, a plurality of sub-blades each provided with a plurality of similar curves similarly positioned and each composed of a plurality of plain faces disposed at angles to each other.
4. In a propeller, a hub provided with a plurality of blades and with a recess and overhang for each blade, and an adjacent hub section provided with a recess to receive the overhang, and an overhang to engage within the recess.
5. In a propeller, a plurality of hub sections, a plurality of blades, the central sec-

tion being provided with two recesses and two overhangs for each blade, and outer hub sections each provided with a recess to receive each of the overhangs of the inner hub section, and an overhang to engage within each of the recesses of such inner hub section.

15

20

In testimony whereof I affix my signature in presence of two witnesses.

THEODORE AMNELIUS.
